CLAIM

The ornamental design for a wind actuated rotating sign, as shown and described.

DESCRIPTION

FIG. 1 is a perspective view of the wind actuated rotating sign incorporating the new design;

FIG. 2 is a front elevational view of the sign of FIG. 1;

FIG. 3 is a rear elevational view of the sign of FIG. 1;

FIG. 4 is a top view of the sign of FIG. 1;

FIG. 5 is a bottom view of the sign of FIG. 1;

FIG. 6 is a side view of the sign of FIG. 1, taken from the side farthest from the brackets which support the sign; and,

FIG. 7 is a side view of the sign of FIG. 1, taken from the side which includes the brackets which support the sign.
